UNITED STATES PATENT OFFICE.

GILBERT P. RITTER, OF CHICAGO, ILLINOIS.

CAR-BOLSTER.

SPECIFICATION forming part of Letters Patent No. 703,609, dated July 1, 1902.

Application filed April 24, 1902. Serial No. 104,516. (No model.)

To all whom it may concern:

Be it known that I, GILBERT P. RITTER, a citizen of the United States, residing at Chicago, in the county of Cook, State of Illinois, have invented certain new and useful Improvements in Car-Bolsters; and I hereby declare the following to be a full, clear, and exact description of the same, reference being had to the accompanying drawings, in which—

- 10 Figure 1 is a side elevation of a car-bolster embodying my invention. Fig. 2 is an under side plan view of the same. Fig. 3 is an enlarged side elevation of the end cap for receiving the ends of the compression and tension members and the spanners of the bolster. Fig. 4 is a longitudinal vertical section of the end cap on the line 4 4, Fig. 6, showing one of the sockets for the end of a compression member of the bolster and one of the seats or 15 sockets for the spanners. Fig. 5 is a similar section on the line 5 5, Fig. 6, showing the opening for the passage of one of the tension-rods or tension members of the bolster. Fig. 6 is an under side plan view of the end cap of the bolster. Fig. 7 is an outer end view of the end cap looking in the direction of the arrow 7, Fig. 3. Fig. 8 is an inner end view of the end cap looking in the direction of the arrow 8, Fig. 3. Fig. 9 is a transverse vertical sectional view 20 of the center casting or strut of the bolster, the center plate omitted. Fig. 10 is a transverse sectional view of the end plate for closing the nut-channel or nut-recess in the outer end of the end cap. Fig. 11 is a view in elevation of the side bearing of the bolster.

Like symbols refer to like parts wherever they occur.

My invention relates to the construction of that class of composite metallic car-bolsters termed "trussed" bolsters, wherein are combined a tension member or members, a compression member or members, and an interposed strut, and has for its object the provision of means whereby the load of the car-body and the torsional strains are properly distributed and transferred to the strut and to the ends of the bolster.

Where trussed structures are used as truck-bolsters, the tension members of the structure are dependent, and the support of the bolster being at the ends where the tension

and compression members unite the strains and load are uniformly distributed throughout the bolster and no material difficulty is experienced in adapting the structure to its 55 position and work; but in the case of body-bolsters, where the structure is reversed—that is, the tension members are uppermost—considerable difficulty is experienced in applying the bolster to the car-body so as to properly distribute the load and strains upon the bolster and prevent sagging of the bolster and car-body. To overcome these difficulties and objections, I have combined with the strut and end sections of a trussed bolster 60 interposed spanners for the support of the car-sills, whereby the tension members of the bolster are relieved of the direct load, which is thereby divided up between the strut or post and the compression members of the 65 structure, and such a construction embodies the main feature of my invention.

A secondary feature of my invention consists in providing the end caps of the bolster structure with inward extensions and combining therewith the spanners and side bearings of the bolster, whereby the tension members are left free and the bolster is cross-braced and stiffened against torsional or transverse strains.

There are other minor features of invention, all as will hereinafter more fully appear.

I will now proceed to describe my invention more fully, so that others skilled in the art to 85 which it appertains may apply the same.

In the drawings, A indicates the strut or post, B the end caps, D the compression members, and E the tension members, of a trussed bolster, which several elements may 90 be of any desired character and with which in practicing my invention are combined spanners S S, interposed between end caps B B and the strut A, so as to act as girders when the sills of the car-body rest thereon.

95 Preferably the compression members D D and the spanners S S are of tubular form and may be rectangular in cross-section; but said compression members may be of any other character desired—as, for instance, T-iron— 100 and the spanners may be plate or T iron, if preferred, and, further, the tension and com-

pression members may be in the same vertical planes, though preferably they are in parallel planes or alternating, as indicated in the drawings.

- 5 For the purposes of illustration the compression members D and spanner members S are herein shown as tubular, the tension members E and compression members D as alternating, while the spanner members S are 10 in the same vertical planes as the compression members D and alternate with the tension members E.

The strut A (see Fig. 9) is or may be a suitable casting provided above or on its upper face with a series of grooves 1 1 1 for the passage of the tension-rods or tension members E, between which are deeper recesses or grooves 2 2 for the passage of the spanners S S, and on its under surface and alternating 20 with the tension-rod grooves 1 1 compression-member grooves 3 3 3, and said strut or post is also provided with the centrally-disposed king-bolt hole 4.

The counterpart of the compression-member grooves 3 3 3 of the strut A are formed 25 on the inner or upper face of the center plate C, (see Figs. 1 and 2,) which latter is riveted or bolted to the strut A when the bolster is assembled.

30 The end caps B, which are preferably malleableized castings, are formed with an inwardly-projecting extension 5 on their upper surface, which may be extended sufficiently to form points of attachment for the side 35 bearing F, (see Figs. 1 and 11,) and are provided with a plurality of sockets 6 6 for the reception of the ends of the compression members D above the same and centrally disposed a plurality of seats or sockets 7 7 for 40 the reception of the ends of the spanners S S and intermediate of the sockets 6 6 passages 8 8 for the tension-rods or tension members E.

The outer end of the end cap B is formed 45 with a chamber or recess 9 for the nuts e of the tension members and is closed when the parts are assembled by means of a cap-plate 10, which may be riveted, bolted, or otherwise secured to the end cap B to conceal the nuts and prevent accidental displacement 50 thereof.

The end caps B and strut or post A being of the general character hereinbefore specified may be cored and flanged in any desired manner, as is well understood in the art, to 55 secure the greatest strength for the least weight.

F indicates a side bearing, which may be of any desired character, provided its general form is of a character to straddle the compression members—as, for instance, provided 60 with the offsets or pillars 11 and recesses 12—and which may be secured by bolting or otherwise to the extension 5 of the end cap B.

The elemental construction of the bolster 65 being substantially as hereinbefore pointed out, the parts may be assembled as follows: The compression members D D, tension mem-

bers E E, spanners S S, strut or post A, and the end caps B B having been assembled so that the spanners S S are above and in line 70 with the compression members D D and intermediate of the tension members E E, (see Figs. 1 and 2,) the center plate C is riveted or bolted to the strut A, so as to confine the compression members D D, and the nuts e 75 on the ends of the tension members are tightened to the desired degree, (to camber the compression members D D, if desired,) after which the cap-plates F are applied and riveted or bolted to the end caps B to close the 80 same and complete the bolster.

Among the advantages incident to body-bolsters as herein described are, first, that the tension members are relieved from the direct load and are free to perform their regular functions in a trussed structure; second, that the load being directly on the spanners is substantially divided between the strut or post and the end caps, the latter being the normal load-points for trussed structures; 90 third, the extreme outer sills are balanced around the point of intersection of the center lines of the tension and compression members of the bolster, thus avoiding bending strains due to the overhang of the side sills, 95 and, fourth, the extension of the end caps and combining therewith of the side bearings stiffens the bolster against cross-bending or torsional strains.

For purposes of illustration and as the preferred construction the spanners S S have been shown as continuous between the end caps B B and as passing over and resting upon the strut or post A, in effect a continuous girder; but, if desired, the spanners may 105 be half-length and socketed into both the strut A and the end cap B with like results.

Having thus described my invention, what I claim, and desire to secure by Letters Patent, is—

1. A trussed car-bolster, provided with spanners for the support of the car-sills, substantially as and for the purposes specified.

2. A trussed car-bolster, provided with spanners for the support of the car-sills, said spanners interposed between the tension members, substantially as and for the purposes specified.

3. A trussed car-bolster, provided with spanners interposed between the tension members and in alignment with the compression members of the bolster, substantially as and for the purposes specified.

4. A trussed car-bolster, comprising in combination, a strut, tension and compression members, spanners, and end caps, the end caps having vertically-aligned sockets for the compression members and spanners, substantially as and for the purposes specified.

5. A trussed car-bolster, comprising in combination, a strut, tension and compression members, spanners, end caps, and side bearings, the end caps having inward extensions for the reception of the side bearings, and the

side bearings arranged to straddle the compression members, substantially as and for the purposes specified.

6. In a trussed bolster, the combination with 5 the tension and compression members thereof, of an end cap having an inward extension, a spanner which engages the inward extension of the end cap, and a side bearing which straddles the compression members and is 10 secured to the inward extension of the end

cap, substantially as and for the purposes specified.

In testimony whereof I affix my signature, in presence of two witnesses, this 23d day of April, 1902.

GILBERT P. RITTER.
